UNITED STATES PATENT OFFICE.

FRANZ A. FULLER, OF NEWARK, NEW JERSEY.

PRESS GUARD.

Application filed August 25, 1923. Serial No. 659,281.

To all whom it may concern:

Be it known that I, FRANZ A. FULLER, a citizen of the United States, residing at Newark, in the county of Essex and State of New Jersey, have invented certain new and useful Improvements in Press Guards, of which the following is a specification.

This invention relates to safety devices as applied to treadle controlled machinery 10 and particularly to such types as power actuated punch presses.

One of the objects of the invention is to provide a barrier or guard with means whereby it is interposed between the operator and danger zone of the press, immediately prior to the descent of the ram or plunger to make contact with the work part disposed on the die or fixed portion of the press.

20 A further purpose is to produce means which prevent operation of the press until the guard has completed contact with the platen of the press, irrespective of treadle movement, thus avoiding premature action 25 of the press likely to damage any intervening object between the guard and platen.

Another aim is in the provision of means to prevent the untimely descent of the guard and hence action of the press.

30 These several aims, objects and purposes, together with others, such as convenience in application, adjustability and efficiency, are attained by the novel construction, combination and arrangement of parts hereafter described and shown in the accompanying drawings, forming a material part of this disclosure, and in which:

Figure 1 is a front elevational view of a conventional type of power punch press, 40 showing the application of an embodiment of the invention.

Figure 2 is a side view of the same.

Figure 3 is a perspective view showing the main operative parts of the invention 45 in detail.

Figure 4 is an enlarged transverse sectional view taken on line 4—4 of Fig. 3.

Figure 5 is a fragmentary side view of the guard latch operating means.

50 Figure 6 is an enlarged sectional view taken on line 6—6 of Figure 1.

An inclined type of punch press is illustrated in the drawing, the same being composed of a body 15, its curved base being ad-

55 justably mounted on legs 16 and having

bearings 17 in its upper portion for the shaft 18.

This shaft extends outward at one end to accommodate a clutch, generally designated by the numeral 19, and beyond the 60 clutch is a heavy belt driven flywheel 20, its hub being engageable with the clutch.

A crank or an eccentric on the shaft actuates an adjustable pitman 21 conveying reciprocal motion to the ram or plunger 65 22, slidably in guides 23 at the front of the press, to which a punch 24 may be attached and on the bed 25 is a bolster 26 to which is clamped the die block 27 carrying a die 28.

The press is put in operation by depressing 70 a treadle or foot lever 29, normally held in a raised position by the tension spring 30, movement of the treadle being communicated to the clutch 19 by a rod 31 which may be adjusted in operative length by a 75 turnbuckle 32.

The foregoing is generally descriptive of any common type of single acting, power operated press and given only to illustrate the application of the invention, the disclosure of which follows.

In place of the rod 31 directly connecting with the clutch device, an arm 33 is pivoted at the rear of the press, at 34, to extend towards the front at either side of the 80 press and to this arm the upper end of the rod 31 is connected and an additional rod 35 is used to connect the arm with the clutch.

Fixed on the forward end of the arm 33 90 is a fork composed of a pair of plates 36 containing slots 37 and at a point rearward of the fork another pair of plates 38 are fixed on the arm, these plates carrying a pivot 39 on which a forwardly extending 95 lever 40 is mounted.

The lever is guided between the plates 36 and has fixed in it a pin 41 operable in the slots 37 limiting the relative motion of the lever and arm and in addition to the weight 100 of the lever, a spring 42 is interposed between the arm and lever tending to press the latter element forcibly downward.

The outer end of the lever is bent to extend, as at 40', in front of the press and has 105 engaged with it an adjustable bar 43 held by clamp screws, this bar extending substantially horizontal in front of the plunger 22.

Attached near the end of the bar 43 is a 110

flat upright stem 44 slotted for vertical adjustment and provided with means for clamping to the bar, this stem being integral with a guard plate 45 extending across the

5 front of the plunger at its lower end and movable by action of the treadle to make contact with the bolster or press bed as shown by the broken lines in Figure 2.

It is to be noted that a full and complete 10 movement of the guard must take place before the clutch rod 35 can be moved to engage the clutch, due to the pin 41 making contact with the upper end of the slot 37, thus preventing it from transmitting suffi-

15 cient movement of the arm 33, in case of some object being interposed between the lower edge of the guard plate 45 and the bolster 26, when the parts are properly adjusted.

20 The guard plate 45 is shown as apertured to permit a view of the work when in its lowered position and is sufficiently rigid to effectively prevent dislocation by the hands of an operator.

25 It is also apparent that if the hands be so placed as to be struck by the guard descending by pressure applied to the treadle, the blow will be cushioned by the spring 42, permitting withdrawal without serious

30 damage being done and that the plunger cannot descend until after such removal of the hands or other objects which may be inadvertently interposed.

In order to maintain the guard in a lowered 35 position and thus assure a reciprocative movement of the plunger, even if the treadle should be released prematurely or before the clutch elements have made operative engagement, the device shown in

40 Figs. 1, 5 and 6 is used.

This device consists of a horizontal bracket 46 rigidly fixed to one of the press plunger guides 23, on the side adjacent the arm and lever, near its lower end, the

45 bracket having a longitudinal slot 47 suited to receive and guide a slide 48 provided with a bevelled outwardly extending end 49 and containing a recess 50, the rear wall 51 of which is also correspondingly bevelled.

50 Access is had to the recess 50 through an opening 52 in the outer wall of the bracket 46, this wall also containing a slot 53 through which extends a pin 54, fixed in the slide 48, to which one end of a ten-

55 sion spring 59 is attached, its outer end being engaged with a pin 60 fixed in the bracket and adapted to draw the slide outwardly.

The latch-like bevelled end 49 of the slide 60 is thus normally held in the path of the arm 33, said arm at its free end being provided with an outwardly extending projection 33' designed to engage with the latch-like bevelled end 49 of the slide when the arm 33 moves downwardly, thereby pressing the

slide back into the bracket, until the arm has fully passed, whereupon the spring 59 draws the slide out, thus preventing the return of the arm.

The slide however is retracted by the bevelled end 61 of an arm 62, rigidly held on the side of the plunger 22, this arm entering the recess 50 and making contact with the element 51, moving the slide 48 back and holding it there, clearing the path of the 75 projection 33' of the arm 33 until the plunger has made its stroke and is beginning to rise to its normal position.

Thus it will be seen that the guard 45 cannot rise prematurely but will remain in 80 downward operative position until the plunger has fully completed its downward stroke and is beginning to rise to its normal upper position, assuring safety to the operator irrespective of treadle action made interveningly.

From the foregoing it will be seen that a simple device for this purpose has been disclosed in the preferred form of its embodiment, but it is not desired to restrict 90 the details to the exact construction shown, it being obvious that changes, not involving the exercise of invention, may be made without conflicting with the scope of the appended claims.

Having thus described my invention, what I claim as new and desire to secure by Letters Patent, is:—

1. In a device of the class described, the combination with a punch press having a 100 frame, a bed, a power driven clutch actuated crank shaft, a plunger operated thereby and a pedal controlling said clutch, of an arm pivoted on said frame, a rod directly connected between said arm and pedal, said arm being operatively engaged with said clutch, a lever pivoted on the arm, means for limiting the relative movement of said arm and lever, said lever having its front end bent to extend in front of said plunger, 105 and a depending guard adjustably secured to said lever.

2. In a device of the class described, the combination with a power punch press, of a guard disposed in front of the plunger, a 110 bar to which the stem element of said guard is adjustably attached, a lever bent to adjustably support said bar, an arm pivoted to the frame of the press, said lever being pivoted on said arm, pedal means for actuating said arm, means for preventing the press from operating prior to the full descent of said guard, a latch on the side of said press, said latch preventing the rise of said arm, and means carried by the plunger 115 of said press for releasing said latch.

3. In a device of the class described, the combination with a punch press having a frame, a bed, a power driven clutch actuated crank shaft, a plunger operated there- 120

by and a pedal controlling said clutch, of an arm pivoted on said frame, a rod directly connected between said arm and pedal, said arm being operatively engaged with said clutch, a lever pivoted on the arm, means for limiting the relative movement of said arm and lever, said lever having its front end bent to extend in front of said plunger, and a guard adjustably carried on said lever, said guard being adapted to make contact with the bed of the press prior to permitting full movement of said arm.

4. In a device of the class described, the combination with a punch press having a frame, a bed, a power driven clutch actuated 15 crank shaft, a plunger operated thereby and a pedal controlling said clutch, of an arm pivoted on said frame, a rod directly connected between said arm and pedal, said arm being operatively engaged with said clutch, a lever pivoted on the arm, means for limiting the relative movement of said arm and lever, said lever having its front end bent to extend in front of said plunger, a guard adjustably carried on said lever, said 20 guard being adapted to swing into contact with the bed of the press prior to the completion of full movement of said arm, a spring actuated sliding latch on the frame of the press normally intercepting the upward movement of said arm, and means carried by said plunger for removing said latch from the path of said arm when said plunger is beginning to rise to its upper position.

25 This specification signed and witnessed 55 this 24th day of August, 1923.

arm until said plate has reached the lowest point permissible by said bed.

5. In a device of the class described, the combination with a punch press having a frame, a bed, a power driven clutch actuated 35 crank shaft, a plunger operated thereby and a pedal controlling said clutch, of an arm pivoted on said frame, a rod directly connected between said arm and pedal, said arm being operatively engaged with said clutch, a lever pivoted on the arm, means for limiting the relative movement of said arm and lever, said lever having its front end bent to extend in front of said plunger, a guard adjustably carried on said lever, said 40 guard being adapted to swing into contact with the bed of the press prior to the completion of full movement of said arm, a spring actuated sliding latch on the frame of the press normally intercepting the upward movement of said arm, and means carried by said plunger for removing said latch from the path of said arm when said plunger is beginning to rise to its upper position.
